MUSICAL INSTRUMENT

Leon Leblanc, Paris, France

Application May 16, 1935, Serial No. 21,881
In France May 22, 1934

2 Claims. (Cl. 84—385)

This invention is directed to an improvement in wind musical instruments, with the improvements particularly applicable to saxophones.

The invention is particularly directed to a modification in the mechanism for the control of the low C $\sharp$, normally open at rest to obtain a more efficient stopping of the hole of low D; to suppress the mechanism of low C $\sharp$ normally closed at rest, and to obtain the emission of the latter by the aid of the little finger of the left hand alone; to stop more effectively low C $\sharp$ while playing notes like B natural and B $\flat$; to arrange the holes of E $\flat$, E natural, F and F $\sharp$ in a predetermined manner to stop the outflow of the condensation of water which is generally produced by these holes, mechanism being included to emit each of these notes by the aid of their corresponding finger-piece alone, without the necessity of employing the finger-pieces of lower conjoined notes to obtain the higher tone; and to vary the shape of the conventional finger-pieces for the little fingers in order to add materially to the convenience of the player.

The invention is illustrated in the accompanying drawings, in which:

Figure 1 is a more or less diagrammatic view showing the mechanism for the control of low C $\sharp$.

Figure 2 is a more or less diagrammatic view showing the change in the arrangement of the 30 holes of high E $\flat$, E, F and F $\sharp$.

Figure 3 is a view of a detail.

With particular reference to Figure 1, conventional studs 1 and 2 support independent rock shafts 3, 4, 5 and 6. A finger-piece 7 is operatively connected to the rock shaft 3 by a bar 8. A finger-piece 9 is operatively connected to the rock shaft 4 by a bar 10. A finger-piece 11 is operatively connected to the rock shaft 5 by a bar 12. Bars 13 and 14 fixed to and projecting from rock shafts 3 and 6 are connected by a rod 15 to cause the rock shafts 3 and 6 to move in unison, that is, in operation of the finger-piece 7. Rock shaft 6 is connected by a bar 16 to the stop of high E $\flat$, indicated at 17. The stop of D, indicated at 18, is connected by a bar 19 to rock shaft 5. A spring 20 carried by stud 1 rests behind a stop 21 on rock shaft 3, while a spring 22 cooperating with a stop 23 on rock shaft 4 is also carried by the stud 1. A spring 24 carried by stud 2 cooperates with a stop 25 on rock shaft 5. The springs in each instance are shown for convenience as free of their stops, it being understood, however, that the spring 20 acts on the rock shaft 3 to hold the finger-piece 7 raised and through the rod 15 to hold the stop

of D closed. The spring 22 acts on the rock shaft 4 to hold the finger-piece 9 raised, while the spring 24 acts on the rock shaft 5 to hold the finger-piece 11 raised and also the stop of hole D raised.

Studs 26 support aligned rock shafts 27 and 28. To the rock shaft 27 is connected a lever 29 extending toward and underlying a lever 30 carried by the rock shaft 4; the rock shaft 28 having a corresponding lever 31 extending toward and underlying a lever 32 on the rock shaft 5. Studs 33 support aligned rock shafts 34 and 35, the rock shaft 34 having a lever 36 extending toward and overlying a lever 37 carried by the rock shaft 27. The rock shaft 35 carries a lever 38 extending toward and overlying a lever 39 carried by the rock shaft 28.

Studs 40 support a rock shaft 41 to which is secured an arm 42 controlling the stop 43 for the hole C $\sharp$. This rock shaft 41 has a lever 44 extending toward and underlying a lever 45 carried by the rock shaft 34. Rock shaft 41 is influenced by spring 46 cooperating with stop pin 47 to be moved when permitted in a direction to maintain the stop 43 in a position to close the hole C $\sharp$. In this connection, it is to be understood that the spring 22 which in operation maintains the finger-piece 9 raised is stronger than the spring 46, so that as long as the spring 22 is free to act, the spring 46 is without influence on the rock shaft 41.

One of the studs 40 and additional studs 48 and 49 support aligned rock shafts 50, 51 and 51 $\times$, rock shafts 50 and 51 through arms 52 and 53, respectively, control stops 54 and 55, respectively, of holes low C and low B. Rock shaft 50 is provided with a rigid bar 56 which overlies a lever 57 projecting from rock shaft 41, and rock shafts 50 and 51 $\times$ are connected for simultaneous movement through a bar 58 connected at 59 and 60 to the respective rock shafts. A rock shaft 61 supported in studs 62 carries a lever 63 which extends toward and overlies a lever 64 carried by the rock shaft 41; the rock shaft 61 also carrying a lever 65 which extends toward and underlies a lever 66 carried by the rock shaft 35. A finger-piece 67 is connected by an arm 68 to the rock shaft 61; a second finger-piece 69 being connected by a bar 70 to the rock shaft 51 $\times$, and a third finger-piece 71 being connected by a bar 72 to rock shaft 50.

It will be remembered that the spring 22 is stronger than spring 46. Therefore, with the parts at rest, the spring 22 holds the rock shaft 4 in position to maintain the finger-piece 9

raised. This lowers the levers 30 and 29, raises the levers 37 and 36, lowers the levers 45 and 44, raises arm 42 and stop 43 of hole C $\sharp$. The effect of spring 46 is thus eliminated as long as the instrument is at rest. If the finger-piece 9 is depressed by the little finger of the right hand, it is quite apparent that the rock shaft 41 is released to the influence of the spring 46 and arm 42 is moved in a direction to cause the stop 43 to close the C $\sharp$ hole. If at this time the finger-piece 67 is depressed by the little finger of the left hand, the rock shaft 42 is correspondingly operated, causing the lever 63 to depress the lever 64 operating the rock shaft 41 against the influence of the spring 46 and raising the stop 43 of the C $\sharp$ hole. Provision is thus made to emit low C $\sharp$ through the operation of the finger-pieces 9 and 67 by the little fingers of the right and left hands. If the finger-piece 9 is released and finger-piece 67 lowered, the lever 65 is raised carrying the lever 66 and lowering the levers 38, 39 and 31. This raises the lever 32, turning the rock shaft 5 against the influence of the spring 24 and closing the stop 18 of hole D. Through this operation, low C $\sharp$ is easily emitted through the operation of the finger-piece 67 by the little finger of the left hand only.

At will, the stop 43 of the hole C $\sharp$ may be closed by the operation of the finger-piece 69 which, operating through the rod 70, the rock shaft 51 $\times$, the bar 58, the rock shaft 50, the lever 56 and the lever 57, will operate the rock shaft 41 to depress the stop 43.

The player is thus given the possibility to depress finger-pieces 9 and 11 and close the stops 43 and 18. B natural and B $\flat$ may thereby be emitted through the use of the little finger of the left hand only on the closing of the holes of C $\sharp$ and D.

In Figure 2, mechanisms are shown to permit the producing of F major, F $\sharp$, E major and high E $\flat$, together with a novel disposition of the holes of these notes, with the particular function to expel the water through these holes, which accumulates and proves troublesome after a prolonged period of closing of the holes.

When the musician plays the saxophone, the instrument is standing in such a position that the water of condensation from blowing goes right through the stop side keys which produce high D, E $\flat$ and F notes, which are situated uppermost on the instrument. Through the present invention the same stops producing D $\sharp$, F and F $\sharp$ are placed on the back of the body of the instrument where there is no water of condensation incident to the position of the instrument when blowing.

Studs 73 support a rock shaft 74 influenced in one direction by a spring 75 carried by one of the studs and engaging behind a pin 76 on the rock shaft. A finger-piece 77 is connected to the rock shaft and the rock shaft further carries a lever 78 which overlies a lever 79 carried on a rock shaft 80 which, together with an aligned rock shaft 80 $\times$, is mounted in studs 81. The spring 75 acts to normally maintain the finger-piece 77 in raised position.

A rock shaft 82 is mounted in alignment with the rock shaft 74, being supported in one of the studs 73, and an additional stud 83. An arm 84 secured to the rock shaft 82 carries a stop 85 for the hole E and a spring 86 carried by the stud 83 and engaging behind a pin 87 influences the rock shaft in a direction to maintain the stop 85 closed.

The rock shaft 80 $\times$ is provided with a lever 88

underlying a lever 89 secured to the rock shaft 82. Pivotal secured beneath and to the rock shaft 80 $\times$ at 90 is a rocker arm 91 which, at the respective ends, is formed to engage stops 92 and 93 carried respectively by the rock shafts 80 and 80 $\times$.

Studs 94 support a rock shaft 95 carrying an arm 96 to which is connected the closure 97 for the high E $\flat$ hole. A spring 98 carried by the stud 94 and cooperating with a pin 99 on the rock shaft 95 influences the rock shaft in a direction to maintain the stop 97 closed. The stop 100 of the adjacent D hole has secured thereto a projection 101 which overlies but is not connected to the stop 97. The rock shaft 95 carries a finger-piece 102 which operates the rock shaft in opposition to the spring 98 and in which operation the stop 97 is raised and through the projection 101, stop 100 is also raised.

A rock shaft 103 is supported in studs 104. These studs are preferably of the conventional double type, the rock shaft 103 being supported in the upper portions of the studs while the lower portions support a rock shaft (not shown) for controlling the stop 105 of the F $\sharp$ hole. Finger-pieces 106 and 107 are secured to the rock shaft 103 and an arm 108 carried by the rock shaft controls the stop 109 of the F major hole. The rock shaft is influenced in a direction to maintain the stop 109 closed by a spring 110 carried by the stud 104 and cooperating with a pin 111 on the rock shaft 103. The rock shaft 103 also carries a lever 112 which underlies the lever 113 on the rock shaft 80. The rock shaft 80 also carries a lever 114 which underlies the arm 96 of the closure 97.

If the player depresses the finger-piece 106 or 107, the closure 109 of hole F is raised against the influence of the spring 110. The lever 112 is also raised, which raises lever 113, actuates 40 rock shaft 80, causing stop 82 on said rock shaft to move one end of the rocker arm 91, causing the opposite end of said arm to engage the stop 93 on the rock shaft 80 $\times$, actuating said rock shaft, raising lever 88 and thereby raising lever 89 and actuating rock shaft 86 to raise stop 85 of hole E major. This operation of rock shaft 80 also raises lever 114 which raises arm 96, raising stop 97 of hole high E $\flat$ and through the projection 101 also raising stop 100 of hole D.

If the player raises stop 109 of hole F major and uses a finger-piece 115, he raises also stop 105 through a projection 116 welded to the stop 105 and overlying the stop 109. This same movement, of course, opens stop 109 of hole F, stop 97 of high E $\flat$, stop 100 of hole D and stop 85 of high E. In depressing the finger-piece 77, the player depresses the lever 78 and lever 79. This rocks shaft 80, raising the lever 114 and actuating the rocker arm 91, thus raising stops 85 of high E, 97 of high E $\flat$ and 100 of D.

It is to be particularly noted that the finger-pieces for the little fingers particularly are in oblong shape in plan, so as to facilitate and accommodate the control of the mechanism 65 through such finger-pieces.

The bar 10 of finger-piece 9 carries a projection 10 $\times$ overlying a projection 12 $\times$ carried by the bar 12 of finger-piece 11 and as finger-piece 11 is connected to rock shaft 5 which carries stop 18, it is apparent that when finger-piece 9 is depressed, finger-piece 11 is likewise depressed and stop 18 operated to close hole D.

What is claimed to be new is:

1. In a wind musical instrument, stops for con- 75

trolling the sounding of F sharp, F, E, and E flat, a single finger piece for controlling each stop independently, and connections whereby the finger piece of the stop for any one of said notes will simultaneously operate the stops for all lower of said notes without recourse to the individual finger pieces for said lower notes.

5 2. In a wind musical instrument, stops for con-

trolling the sounding of F sharp, F, E, E flat, and D, a single finger piece for controlling each stop independently, and connections whereby the finger piece of the stop for any one of said notes will simultaneously operate the stops for all 5 lower of said notes without recourse to the individual finger pieces for said lower notes.

LEON LEBLANC.
